UNITED STATES PATENT OFFICE.

BERNARD F. FRIZZELL, OF BALTIMORE, MARYLAND.

BOILER-FEED CONTROL.

1,091,742.

Specification of Letters Patent. Patented Mar. 31, 1914.

Application filed January 23, 1912. Serial No. 672,821.

To all whom it may concern:

Be it known that I, BERNARD F. FRIZZELL, a citizen of the United States, residing at Baltimore, State of Maryland, have invented 5 certain new and useful Improvements in Boiler-Feed Control; and I do hereby declare the following to be a full, clear, and exact description of the invention, such as will enable others skilled in the art to which it appertains to make and use the same.

10 This invention relates to an apparatus for controlling feed water boilers, and has particular application to a removable container which is in the nature of a flat expansible 15 box which is designed to permanently contain and hold a fluid, such as water, which readily responds to changes in temperature, this feature, namely, inclosing the fluid in a continuous practically airtight expansible 20 box, positively obviating the disadvantages and annoyances caused by vaporization of the usual fluids employed in devices of this character.

25 With the above object in view the invention consists of certain novel details of construction and combination of parts herein-after fully described and claimed, it being understood that various modifications may be made in the minor details of construction 30 within the scope of the appended claims.

35 In the accompanying drawing forming part of this specification, the figure is a longitudinal sectional view through the expansible box chamber and feed water controlling mechanism.

40 Referring now to the drawing in which like characters of reference designate similar parts, 10 designates a boiler having its steam and water spaces connected respectively by pipes 11 and 12 with a water and steam chamber 13 located at the average or 45 normal water line level of the boiler. The chamber 13 is formed in the lower part of the casing 14, the casing being closed by a cover 15 which forms a practically airtight chamber 16 in the top of the casing, both chambers being separated by a heat conducting partition 17.

50 Within the chamber 16 I arrange an expansible box 18 in the nature of a hollow disk formed of elastic or resilient material, the hollow disk or box being filled with an expansible liquid of any character which will respond quickly to changes in temperature. The box is hermetically sealed whereby to prevent entry of air or escape of the

contents. The cover is provided with a central bearing 19 in which is slidably fitted a piston 20, the head of the piston bearing against the top of the expansible box and being yieldingly held in this position through the instrumentality of a helical spring 21 which bears upon the piston head and end wall of the bearing as clearly shown.

55 As the water level in the boiler fluctuates the boiler steam and water alternately fill the chamber 13. It is well known that water communicating with a boiler, but cut off from circulation, becomes cold, and therefore when the chamber 13 is filled with water the casing 14 is comparatively cool. When the water level in the boiler falls below the chamber 13 the latter is filled with 60 fresh steam which as soon as it condenses 70 settles in the chamber, the chamber in this manner being heated by the fresh steam. During such heating of the chamber there will be a resultant expansion of the expansible box 18. The presence of steam in 75 the chamber at low water will cause an increase of temperature in the chamber 16 with a resultant expansion of the expansible box. During such expansion the piston will be raised against the tension of the 80 spring, and through the instrumentality of mechanism to be presently described, will cause the water supply in the boiler to be replenished. When this takes place water will again enter the chamber 13 with a resultant decrease of temperature in the chamber 16 and contraction of the box 18, and during such movement of the box the piston will be returned to its initial position 85 by the spring 21 and the water supply controlling mechanism returned to inactive position.

90 The water supply controlling mechanism includes a valve casing 22, there being spaced ports 23 and 24 on one side of the casing and a port 25 on the opposite side of the casing intermediate these ports. A valve stem 26 is mounted within the casing having a plug valve 27. A connecting rod 28 is adjustably secured to the piston rod 20 95 and is secured to the valve stem 26 as shown. It will be seen that when the expansible box 18 is in quiescent position, the plug valve 27 is in such a position as to unseal the port 25 and to permit of communication of 100 this port with the port 24. Upon expansion 110 of the box 18, the plug valve 27 will be

moved to such a position as to cut off communication between the ports 25 and 24, and to establish communication between the ports 25 and 23.

5 A chamber 28 is connected by a conductor pipe 29 to the port 25. A diaphragm 30 is disposed within the chamber, and a spring controlled piston 31 bears against the diaphragm, the piston stem 32 entering a valve 10 casing 33 interposed in a steam pipe 34 and being equipped with a valve 35 adapted to open and close the passage in the steam pipe. The steam pipe leads to the steam cylinder 36 of a pump 37 having a supply pipe 38 15 which leads to any suitable water supply, and a feed pipe 39 which leads into the water space of the boiler.

The port 23 of the valve casing 22 is connected in any suitable manner with a water 20 supply under pressure, preferably a city hydrant. Now when the expansible box is in quiescent position, and the plug valve 27 in such a position to unseal the port 25 and to permit of communication between this 25 port and the port 24, which latter it may be said is simply a drain, water may back through the pipe 29 and relieve the diaphragm 30 from pressure so that the valve 35 closes the steam pipe 34. On the other 30 hand when the plug valve 27 is moved to such a position as to cut off communication between the ports 24 and 25 and to establish communication between the ports 25 and 23, 35 upon expansion of the expansible box, water under city pressure will flow through the water pipe 29 and act upon the diaphragm 30 so as to cause the latter to move the valve 35 to open position and permit of the pas-

sage of steam through the steam pipe for actuating the pump. The pump will supply 40 water to the boiler until the normal supply or in other words the normal water level is reached whereupon the valve 35 will be closed as above described to stop the pump.

What is claimed, is:—

1. In a feed water regulator, the combination with a chamber, of a resilient removable container located within the chamber and having a fluid permanently sealed therein which is adapted to vaporize under a rise 50 in temperature to expand the container, the decrease in temperature and consequent condensation of the fluid causing the container to resume its normal position, and a regulating device controlled by the movement of 55 the wall of the container independently of the walls of the chamber.

2. In a thermostatic regulator, the combination with a fluid containing chamber, of a container consisting of a closed receptacle 60 without pipe connections and having a resilient wall, and having permanently sealed therein a material which is expansible by heat, a regulating device whose movements are controlled by the movements of a wall 65 of the container and means for supporting said container in a position exposed to the heat of the fluid in said chamber, but separated therefrom by a substantially rigid wall.

In testimony whereof, I affix my signature, in presence of two witnesses.

BERNARD F. FRIZZELL.
